UNITED STATES PATENT OFFICE.

JOHN NILSEN SELVIG, OF CHICAGO, ILLINOIS, ASSIGNOR TO WESTERN ELECTRIC COMPANY, INCORPORATED, OF NEW YORK, N. Y., A CORPORATION OF NEW YORK.

WIRE-DRAWING MACHINE.

Application filed June 6, 1922. Serial No. 566,385.

This invention relates to improvements in wire drawing machines.

One feature of the invention is the provision of a wire drawing machine, having a 5 guide roll, a capstan or drawing element and a driving mechanism therefor, with a clutch mechanism mounted within the capstan or drawing element and means for operating the clutch mechanism to uncouple 10 the capstan from the driving mechanism in the event that the wire breaks during the drawing operation.

An additional feature of the invention is 15 the inclusion in a wire drawing machine of the type above described, of a braking mechanism for the drawing means which is operated in the event that the wire breaks.

Another feature of the invention is the 20 inclusion, in a machine of the type above described, of a take-up spool, mechanism for varying the speed of the take-up spool to maintain a uniform tension on the wire between the drawing element and the take-up spool, and means responsive to the tension 25 of the wire for both actuating the tension control mechanism and the clutch for uncoupling the capstan or drawing element from its driving mechanism in the event that the wire breaks during the drawing operation.

By mounting the clutch mechanism within the capstan a minimum number of operative connections are provided between the driving mechanism and the capstan or drawing element, so that power for driving the 35 drawing element is conserved, the mechanism made capable of high speed operation, and the machine rendered compact and a saving of floor space effected. The provision of a single mechanism for both maintaining a uniform tension on the wire between the take-up spool and capstan and for stopping the operation of the latter in the 40 event that the wire breaks, result in a coordination of these functions and a simplification of the machine. By providing a means for operating the clutch device to stop the capstan in the event that the wire breaks during the drawing operation, difficulties incident with the breakage of the 45 wire, such as tangling of the wire supplied to the wire drawing apparatus, the disarrangement of the wire strung on the ma-

chine, dislodgment of the dies from their holder, or the tangling of the stored wire are 55 in many instances entirely prevented and in all cases materially reduced.

Other objects and advantages of the present invention will be set forth in the following description and particularly pointed 60 out in the appended claims.

The drawings illustrate one embodiment of the invention, in which—

Fig. 1 is a front elevation of a machine embodying the features of the invention; 65

Fig. 2 is an enlarged fragmentary side elevation, partly in section, showing the lever connections for operating the capstan clutch;

Fig. 3 is an enlarged fragmentary side 70 elevation, partly in section, showing the clutch mechanism mounted within the capstan;

Fig. 4 is an enlarged skeleton view, partly broken away, showing the mechanism for 75 controlling the speed of the take-up spool;

Fig. 5 is an enlarged vertical sectional view showing in detail a portion of the mechanism shown in Fig. 4;

Figs. 6 and 7 are enlarged fragmentary 80 detail views in vertical section, parts being shown in elevation, of a portion of the lever mechanism for operating the capstan clutch shown in Fig. 2.

Fig. 8 is an enlarged fragmentary horizontal sectional view taken on the line 8—8 of Fig. 6, and

Fig. 9 is an enlarged, fragmentary, disassembled perspective view showing in detail 90 a portion of the mechanism illustrated in Fig. 6.

Referring now to the drawings in detail in which like reference numerals designate similar parts throughout the several views, 10 represents a frame work which supports a 95 compartment 5 of substantially rectangular shape having top, bottom, back, and side walls 11, 12, 13, and 14 respectively. The front of the compartment may be closed by sliding doors 100 and 101 of the type fully 100 shown and described in a co-pending application of W. F. Hosford, Serial No. 566,206, filed June 6, 1922. The wire drawing apparatus is mounted within the compartment 5 and comprises a horizontal shaft 18, upon 105 which is mounted a plurality of integral

5 capstans 17-17 of different diameters. Supported above the shaft 18 are a plurality of sheaves 19 independently mounted upon a horizontally disposed shaft 20 suitably supported within the compartment 5. Mounted between the sheaves 19 and capstans 17-17 is a die block 21 also suitably supported within the compartment 5.

10 A supply of wire to be reduced in diameter is carried by a supply spool 50 suitably mounted at the front of the machine. The wire is guided from the supply spool over and under pulleys 51 and 52 respectively (Fig. 1) and then over the rear sheave 19 and through the first reducing die (not shown) carried by the die block 21. The wire is then wound once around the capstan 17 of smallest diameter after which it is passed upward and over the next sheave 19 and through the next reducing die carried by the die block 21. The wire is then wound around the next capstan and then again over the next sheave 19 and through the next reducing die, etc., until it is finally drawn 25 down to the desired diameter by the last reducing die. From the final reducing die the drawn wire passes around the capstan 17 of largest diameter and is guided by a pulley 57 mounted on a stationary arm 58 adjustably positioned on the shaft 20. From the pulley 57 the wire passes through an opening 121 in the closed doors 100 and 101 to a pulley 59 carried by an arm 60 and thence is led to a take-up spool 61 driven by mechanism hereinafter to be described.

40 The clutch mechanism for connecting the capstans 17-17 to and disconnecting them from the shaft 18 is illustrated in Figs. 2 and 3 of the drawings, the clutch being shown in its operated position. The shaft 18 is in the form of a sleeve which projects through a horizontally and centrally disposed opening made through the capstans 17-17 and carries adjacent its outer end (Fig. 3) an annular member 70 fast thereto which has secured to it by means of a pin 71 a plurality of clutch disks 72. Alternately mounted between the clutch disks 72 are clutch disks 73 which are secured by a pin 74 to the inner 45 peripheral wall of a cup-shaped opening 75 made in the capstans 17-17. The disks 72 and 73 are movable longitudinally on the pins 71 and 74 respectively, and when pressure is exerted to force the disks together they form a driving connection between the capstans 17-17 and the sleeve 18, as is readily understood. Means for forcing the disks 72 and 73 together comprises a plate 76 which engages the outermost disk, and when the said plate is moved toward the right into the position shown, serves to force the disks together sufficiently to cause them to rotate as a unit. The plate 76 is fastened to one end of a shaft 77 mounted within the sleeve 18. A transverse pin 79 is secured to the

50 shaft 77 and projects through diametrically opposite longitudinal slots 80 made in the sleeve 18 and engages an annular channel formed in the inner wall of a housing 78 so as to be movable longitudinally therewith but free to rotate independently of the said housing. Through the medium of the pin 79 and slots 80 the shaft 77 and housing 78 are movable together longitudinally of the sleeve 18. Means (not shown) is provided 55 for preventing the housing from turning but permitting it to move longitudinally of the sleeve 18. Secured to the sides of the housing 78 at diametrically opposite points are pins 81 which receive the bifurcated ends of a forked member 82 which is pivoted at 83 along with a link 84. The link has secured to its free end a pin 85 which fits within a slot formed in the upper end of a vertically reciprocable rod 86. For a more detailed 60 illustration and description of the clutch mechanism per se reference is made to the co-pending application of W. F. Hosford, Serial No. 566,206, filed June 6, 1922.

65 The sleeve 18 is driven by a bevel gear 32 (Fig. 2) secured thereto, this gear meshing with a bevel gear 33 fast upon a shaft 34 which is driven through suitable mechanism by a motor or other source of power (not shown).

70 In wire drawing machines the former practice has been to connect the capstan by intermediate shafting to a clutch mechanism mounted apart therefrom. By mounting the clutch mechanism within the capstan this intermediate shafting is dispensed with, resulting in a conservation of power and permitting higher speed operation. Furthermore, the capstan provides a housing for the clutch mechanism and since both the capstan and clutch mechanism only occupy the space necessary for the capstan alone, the over-all width of the machine is materially reduced and a saving of considerable 75 floor space effected.

80 As previously stated, the clutch mechanism shown in Fig. 3 is illustrated in its operated position in which the capstans 17-17 are connected with the sleeve 18. When it is desired to release the clutch mechanism and stop the operation of the capstans 17-17, a knob 125 is moved to the left, as viewed in Figs. 2 and 7. This knob is mounted on the projecting end of a rod 126 by a pin 127, fastened to the knob, which fits within a longitudinal slot 128 cut in the rod. Due to this connection the knob 125 may move a limited distance on the rod without causing any movement of the latter. The rod 126 is reciprocably mounted within a bracket 129 fastened to the front wall of the compartment 5. When the capstan is operating, the rod 126 is held in the position shown in Fig. 7 by means of a 85 spring pressed pawl 130 which engages a 90

notch cut in the rod. When the knob 125 is moved to the left to stop the operation of the capstan, as above described, a shoulder 131 formed on the knob engages a projection 132 integral with the pawl 130 causing the said pawl to be rotated counterclockwise and free the rod 126 which is moved toward the left by a compression spring 153 (Fig. 6) to be hereinafter more fully described. Pivoted to the rod 126 at a point 133 is a lever 134 which is pivoted at one end to the bracket 129 and at its other end to one end of a link 135, the other end of which is pivoted to a bell-crank lever 136 pivotally mounted upon a bracket 137 secured to a portion of the framework of the machine, (Fig. 2). The bell-crank lever 136 is also pivoted to one end of a link 138, the other end of which is connected to the laterally extending arm 139 of a bell-crank lever 140. This lever is pivoted on a stud shaft 141 (Fig. 6) carried by a bracket 142 fastened to a portion of the framework 10. The other arm 143 of the bell-crank lever 140 is bifurcated to straddle one end of a rod 144 to which it is pivotally connected by means of a stud 145. The rod 144 is reciprocably mounted within the bracket 142 and is prevented from turning by means of 30 a pin 146 carried by the said bracket which fits within a longitudinal slot 147 cut in the said rod. The inner end of the rod 144 has a tongue portion 148 and a lug 149 on either side thereof as shown in Fig. 9. When the 35 capstan is operating, the end of the rod 144 fits within a longitudinal slot 150, cut in a block 151, in a position in which the lugs 149 rest beneath lugs 152 which narrow the front portion of the slot to a width which 40 is only sufficient to receive the tongue portion 148. When the knob 125 is moved as previously described, through the rod 126, lever 134, link 135, bell-crank 136, link 138, and bell-crank 140, the rod 144 is moved toward the right, as viewed in Fig. 6, by the 45 compression spring 153 which bears at one end against a shoulder formed on the rod 144 and at its other end against a plug 154. The rod 144 is moved a sufficient distance to 50 carry the lugs 149 from beneath the lugs 152 and permit the block 151 to freely slide on the tongue 148. The block 151 is circular in cross section and is reciprocably mounted within an opening formed in a projecting portion 155 carried by the framework of 55 the machine. When the block 151 is freed by the rod 144, it is moved downwardly, as viewed in Fig. 6, by means of energy stored in a compression spring 156 which bears at 60 one end against a collar 157, which is in engagement with lock nuts 158 threaded on a rod 159, the other end of said spring engaging the bottom of a cup-shaped opening 160 formed in the block 151. In moving 65 downwardly the block 151 engages the up-

per edge of a vertically disposed casing 161 into which an enlarged portion of rod 159 projects and to which the said rod is attached by means of a pin 162 carried by the casing which is movable within a longitudinal slot 163 cut in the rod 159. The tension of the spring 156 is sufficient to couple the block 151 to the casing 161 and rod 159 so that these three parts move together as a unit during the downward movement of the block. The casing 161 is pivoted at 164 to a foot pedal 97', the purpose of which will be hereinafter described. Threaded on the upper end of the rod 159 are nuts 165 and 166 which clamp between them a block 167 carrying at diametrically opposite points pivot pins 168 upon which the bifurcated ends of a lever 92 are pivoted. The lever 92 is pivotally mounted at 93 upon a bracket 94 carried by the framework 10, and is connected by a link 91 with the rod 86 (Figs. 2 and 3). After the block 151 has been coupled to the casing 161 and rod 159 through the medium of the spring 156, as previously described, these three elements are moved downwardly, a distance limited by the engagement of a brake member 89 carried by the housing 78 with the annular member 90 carried by the capstan, which movement will be described presently, the lever 92 being rocked clockwise about its pivot 93 by an upward movement of the rod 86. The rod 86 is moved in this direction, through the link 84, fork member 82 and casing 78, by the rod 77 which is moved toward the left, as viewed in Fig. 3, by means of energy stored in a compression spring 87 which is released by the actuation of the knob 125, as hereinbefore described. The spring 87 has one of its ends in engagement with the said shaft and its other end against a plug 88 screwed into the end of the shaft 18. The rod 77 moving toward the left carries with it the plate 76, thereby relieving the pressure on the clutch disks 72 and 73 so that these disks no longer couple the capstans 17—17 to the sleeve 18. The housing 78 is limited in its movement toward the left, as hereinbefore described, by the engagement of the brake member 89 carried thereby with an annular member 90 rotatable with the capstans 17—17 the braking surface serving to stop the rotation of the capstans after the clutch mechanism is released.

movement of which rocks the lever 92 counter-clockwise as viewed in Fig. 2 about its pivot 93. This movement of the link 92 draws the rod 86 downwardly (Figs. 2 and 3) which through the medium of the link 84, fork member 82, and housing 78 moves the rod 77 to the right, as viewed in Fig. 3, against the spring 87. As the housing 78 and rod 77 are moved toward the right, the 10 brake member 89 carried by the housing 78 moves out of engagement with the annular member 90, thereby freeing the capstan, the further movement of the rod 77 causing the plate 76 carried thereby to force the clutch disks 72 and 73 into engagement with each 15 other so that they form a driving connection between the capstans 17—17 and the sleeve 18. As the rod 159 is moved upwardly to operate the clutch mechanism, as above described, the operator pulls outwardly on the knob 125 and when the block 151 has been moved upwardly, through the medium of casing 161 and rod 159, a distance sufficient to bring the lugs 149 opposite the wide 20 portion of the slot 150, the rod 144 may be moved toward the left, as viewed in Figs. 8 and 9 until the said lugs rest beneath the projections 152 formed in the slot. When the rod 144 is in this position it supports 25 the block 151 in its upwardly moved position, and the block in turn through the medium of spring 156, which is stronger than spring 87, holds the rod 159 in its upwardly moved position. The rod 159, through the 30 lever system heretofore described, retains the housing 78 and shaft 77 in such position that the plate 76 locks the clutch disks 72 and 73 together. The rod 144 is retained in its locking position through the system 35 of levers connecting it with the rod 126 the latter rod being locked in its outwardly moved position by means of the spring 40 pressed pawl 130.

After the clutch mechanism has been actuated through the foot pedal 97' to connect the capstan with the driving mechanism and the said clutch has been locked through the actuation of the knob 125, the foot pedal 97' may be released, which is returned to its initial elevated position by the weight of the casing 161 which moves downwardly a distance limited by the pin 162 and slot 163.

The mechanism for driving the take-up spool 61 at varying speeds to compensate for the varying diameters thereof as wire is stored on the spool, which mechanism includes a friction clutch the driving action of which is controlled by the tension of the drawn wire, will now be described. A suitable gearing (not shown) drives a horizontal shaft 40 (Fig. 4) positioned a short distance below the shaft 18. The shaft 40 extends into a housing 41 (Fig. 1) and carries at its forward end a worm gear 42 (Fig. 4) which 60 meshes with a worm 43 formed on a sleeve

45 rotatable in suitable bearings (not shown) carried by the housing 41. One end of the sleeve has secured thereto a disk clutch member 48. Extending through the sleeve 45 and rotatable independently thereof is a 70 spindle 52 having splined thereon a clutch disk member 54. The take-up spool 61 is suitably secured to the spindle 52 so as to rotate therewith. The clutch disks 48 and 54 are normally held out of engagement with 75 each other by means of a spring 59'. When the disks are in engagement they form a driving connection between the sleeve 45 and shaft 52 so that the take-up spool 61 is driven by the shaft 40. The driving engagement of 80 the disks 48 and 54 is controlled by suitable leverage mechanism indicated generally by reference numeral 200. This mechanism includes the arm 60 having pivotally mounted thereon the pulley 59 over which the drawn 85 wire passes to the take-up spool 61. For a detailed disclosure and description of the mode of operation of the leverage mechanism 200 to vary the speed of the take-up spool 61 responsive to the tension on the drawn wire 90 between the take-up spool and last reducing die, reference is made to my co-pending application, Serial No. 541,633, filed March 7, 1922, since this mechanism is identical with that disclosed in my application above referred to.

As is described in my said application, Serial No. 541,633, when the tension on the drawn wire is decreased below the proper tension, the leverage mechanism 200 is actuated to increase the speed of the take-up spool, and in this operation, the link 97, which is one element of the said leverage mechanism, is moved downwardly. When the tension on the drawn wire is increased above the proper tension, the said link is moved upwardly. In the event that the wire breaks, the link 97 is caused to move downwardly a distance sufficient to move a plate 112 carried by the link into engagement with a collar 121' and cause a downward movement thereof. The collar 121' is carried by a rod 119' the upper end of which is pivoted at 120' (Fig. 7) to an arm 122' fast on a shaft 123' which also has secured thereto the spring pressed pawl 130. In the event that the wire breaks during the drawing operation and the rod 119' is depressed, it causes arm 122' to turn the shaft 123' counter-clockwise, as viewed in Fig. 7. This movement of shaft 123' disengages pawl 130 so that the rod 126 is free to move inwardly to disengage the clutch mechanism within the capstan in the same manner that the said rod 126 is freed by disengaging the pawl 130 through an actuation of knob 125 which operation has been previously described.

From the above it will be understood that the link 97 which is actuated responsive to the tension of the drawn wire to operate the 130

mechanism for varying the speed of the take-up spool, also in the event that the strand breaks, actuates means for tripping the pawl 130 which releases the mechanism for disengaging the clutch mechanism mounted with-
5 in the capstan to stop the operation thereof.

What is claimed is:

1. In a wire drawing machine, a die block 10 designed to support a plurality of dies, two shafts, a series of sheaves independently mounted on one shaft, a capstan mounted on, the other shaft, means for driving said shaft, a clutch mechanism located within the capstan for operatively connecting the capstan 15 with the shaft, a wire storage mechanism, and means associated with the wire between the capstan and said storage mechanism for operating said clutch mechanism to stop the capstan in the event that the wire breaks.

2. In a wire drawing machine, a die block 20 designed to support a plurality of dies, a pair of shafts, a plurality of sheaves independently mounted on one of said shafts, a capstan mounted on the other shaft, means for driving said shaft, a friction clutch mechanism for operatively connecting the capstan with the shaft, a wire storage mechanism, and means associated with the wire 25 between the capstan and wire storage mechanism for operating the clutch mechanism to stop the capstan in the event that the wire breaks.

3. In a wire drawing machine, a die block 30 designed to support a plurality of dies, a pair of shafts, a plurality of sheaves independently mounted on one of said shafts, a capstan mounted on the other shaft, means for driving said shaft, a friction clutch mechanism within said capstan for operatively connecting the capstan with the shaft, a wire storage mechanism, and means associated with the wire between the capstan and the wire storage mechanism for operating the clutch mechanism to stop the capstan 40 in the event that the wire breaks.

4. In a wire drawing machine, a die block 45 designed to support a plurality of dies, a shaft, a plurality of sheaves independently mounted thereon, a driving shaft, a capstan mounted thereon, a friction clutch mechanism within said capstan for operatively connecting the capstan with the driving shaft, a wire storage mechanism, a recipro-
50 cale member and means associated with the wire between the capstan and said storage mechanism for reciprocating said member to operate the clutch mechanism.

5. In a wire drawing machine, a die block 60 designed to support a die, a guide roll, a drawing element, a take-up spool, driving means for said drawing element and take-up spool, a clutch mechanism for operatively connecting and disconnecting said drawing element to and from said driving means, mechanism for operating said clutch mechanism for varying the speed of the take-up spool, 65

nism to stop the operation of the drawing element in the event that the wire breaks, and means for controlling the speed of the take-up spool to maintain a uniform tension in the wire.

6. In a wire drawing machine, a die block 70 designed to support a die, a guide roll, a drawing element, a take-up spool, driving means for said drawing element and take-up spool, clutch mechanism for operatively 75 connecting and disconnecting said drawing element to and from said driving means, control means for varying the speed of the take-up spool, and means for operating said clutch mechanism and said control means. 80

7. In a wire drawing machine, a die block 85 designed to support a die, a guide roll, a drawing element, a take-up spool, driving means for said drawing element and take-up spool, clutch mechanism for operatively connecting and disconnecting said drawing element to and from said driving means, control means for varying the speed of the take-up spool and means responsive to the tension in the strand between the take-up 90 spool and drawing element for controlling the clutch mechanism and said control means.

8. In a wire drawing machine, a die block 95 designed to support a die, a guide roll, a drawing element, a take-up spool, driving means for said drawing element and take-up spool, a clutch mechanism mounted within said drawing element for operatively connecting and disconnecting it to and from said driving means, control means for varying the speed of the take-up spool, and means responsive to the tension in the wire 100 between the take-up spool and drawing element for controlling the clutch mechanism 105 and said control means.

9. In a wire drawing machine, a die block 110 designed to support a die, a guide roll, a drawing element, driving means for the drawing element, a take-up spool, a clutch 115 mechanism for operatively connecting and disconnecting the drawing element to and from the driving means, mechanism for operating the clutch mechanism to disconnect the drawing element from the driving means 116 in the event that the wire breaks, and means for controlling the speed of the take-up spool to maintain a uniform tension in the wire.

10. In a wire drawing machine, a die 120 block designed to support a die, a guide roll, a drawing element, a take-up spool, driving means for the drawing element and the take-up spool, clutch mechanism for operatively connecting and disconnecting the 125 drawing element to and from the driving means, mechanism for operating the clutch mechanism to disconnect the drawing element from the driving means, control means for varying the speed of the take-up spool, 130

and means for operating both the last mentioned mechanism and the control means in the event that the wire breaks.

11. In a wire drawing machine, a die block designed to support a die, a guide roll, a drawing element, a take-up spool, driving means for the drawing element and the take-up spool, a clutch mechanism for operatively connecting and disconnecting the drawing element to and from the driving means, braking means for the drawing element, mechanism for operating the clutch mechanism to disconnect the drawing element from the driving means and to apply the braking means to the drawing element in the event that the wire breaks, and means responsive to the tension in the wire between the take-up spool and the drawing element for controlling the speed of the take-up spool to maintain a uniform tension in the wire.

12. In a wire drawing machine, a die block designed to support a die, a guide roll, a drawing element, a take-up spool, driving means for the drawing element, a take-up spool, driving means for the drawing element and take-up spool, a clutch mechanism for operatively connecting and disconnecting the drawing element to and from the driving means, braking means for the drawing element, control means for varying the speed of the take-up spool, and means associated with the wire between the take-up spool and the drawing element for controlling the clutch mechanism, the braking means and the control means.

13. In a wire drawing machine, a die block designed to support a die, a guide roll, a drawing element, driving means therefor, braking means for the drawing element and mechanism for operating the braking means in the event that the wire breaks.

14. In a wire drawing machine, a guide roll rotatable around a horizontal axis, a wire drawing element rotating around a horizontal axis disposed below and in substantially the same vertical plane as the axis of the guide roll, a die block designed to support a die located between the guide roll and the drawing element, braking means for the drawing element, and mechanism for operating the braking means in the event that the wire breaks.

15. In a wire drawing machine, a die block designed to support a die, a guide roll, a drawing element, driving means for the drawing element, braking means associated with the drawing element, a storage mechanism, and means controlled by the wire between the drawing element and the storage mechanism for operating the braking means in the event that the wire breaks.

16. In a wire drawing machine, a die block designed to support a plurality of dies, two shafts, a series of sheaves independently mounted on the upper shaft, said

mounted on one shaft, a capstan mounted on the other shaft, means for driving the last mentioned shaft, braking means associated with the drawing means, and means for operating the braking means in the event that the wire breaks.

17. In a wire drawing machine, a die block designed to support a die, a guide roll, a drawing element, driving means therefor, braking means for the drawing element, and mechanism for disconnecting the drawing element from the driving means and operating the braking means in the event that the wire breaks.

18. In a wire drawing machine, a die block designed to support a die, a guide roll, a drawing element, driving means for the drawing element, mechanism for operatively connecting and disconnecting the drawing element to and from the driving means, a storage mechanism, braking means associated with the drawing element, and means controlled by the wire between the drawing element and the storage mechanism for operating the mechanism to disconnect the drawing element from the driving means and for operating the braking means in the event that the wire breaks.

19. In a wire drawing machine, a die block designed to support a plurality of dies, two shafts, a series of sheaves independently mounted on one shaft, a capstan mounted on the other shaft, means for driving the last mentioned shaft, a clutch mechanism located within the capstan for operatively connecting the capstan to and disconnecting it from its associated shaft, braking means for the capstan, and means for operating the clutch mechanism to disconnect the capstan from the associated shaft and for operating the braking means in the event that the wire breaks.

20. In a wire drawing machine, a die block designed to support a plurality of dies, a pair of shafts, a plurality of sheaves independently mounted on one of the shafts, a capstan mounted on the other, driving means for driving the last mentioned shaft, a friction clutch mechanism located within the capstan for operatively connecting the capstan to and disconnecting it from its associated shaft, a braking means for the capstan, a wire storage mechanism, and means associated with the wire between the capstan and the wire storage mechanism for operating the clutch mechanism to disconnect the capstan from its associated shaft and to apply the braking means to the capstan in the event that the wire breaks.

21. In a wire drawing machine, a pair of horizontal shafts disposed one above the other in substantially the same vertical plane, a stepped capstan mounted on the lower shaft, a series of sheaves independently mounted on the upper shaft, said

- sheaves being of uniform diameter and the diameter thereof being less than the diameter of the largest stepped portion of the capstan, a die block designed to support 5 a plurality of dies located between the capstan and the sheaves, means for driving the lower shaft, a clutch mechanism located within the capstan for operatively connecting the capstan to and disconnecting it from 10 its associated shaft, braking means for the capstan, a wire storage mechanism, and means associated with the wire between the capstan and the storage mechanism to operate the clutch mechanism to disconnect the capstan from its associated shaft and to apply the braking means to the capstan in the event that the wire breaks. 15

In witness whereof, I hereunto subscribe my name this 31st day of May, A. D. 1922.

JOHN NILSEN SELVIG.
